UNITED STATES PATENT OFFICE.

FRANK BATT, OF NORTH TONAWANDA, NEW YORK.

TRANSPORTATION-TICKET.

1,107,743.

Specification of Letters Patent. Patented Aug. 18, 1914.

Application filed November 1, 1912. Serial No. 729,024.

To all whom it may concern:

Be it known that I, FRANK BATT, a citizen of the United States, residing at North Tonawanda, county of Niagara, and State 5 of New York, have invented certain new and useful Improvements in Transportation-Tickets, of which the following is a specification.

My invention relates to certain new and 10 useful improvements in transportation tickets and particularly such as consists of a plurality of detachable sections or coupons.

While this ticket is particularly designed 15 for use or interurban street car lines it may be used to good advantage on steam and ferry boats and in other place or places where payment is to be made for transportation from one point to another, and when 20 desired, for return to the starting point.

The primary object of my invention is the production of a ticket by the use of 25 which dishonesty among conductors or other employees handling the tickets will be eliminated, it being the purpose of this invention to provide a ticket that cannot again be sold or used by dishonest employees for future passage after having been once used for such purpose, thus preventing employees 30 defrauding the owners of the transportation lines of the regular fare for such travel.

A further object of my invention is to provide means whereby the passenger may ascertain, when the conductor or other employee 35 takes up any ticket section or coupon for passage, whether or not he has properly voided or canceled such detached section or coupon so that it cannot again be used for passage.

Another object of my invention is to provide each of the ticket sections or coupons 40 with designated primary punch points and preferably all succeeding coupons with related secondary punch points, and to provide a folded ticket so that when punching each of the ticket sections or coupons, the punch will be made to penetrate all the sections or coupons then remaining.

Still another object is to provide means 45 whereby it may be determined at a glance, when all the ticket sections or coupons are returned to the auditor's office, whether or not the conductor has properly punched the ticket.

With these and other objects in view the invention consists in a strip of paper or

cardboard comprising a plurality of connected ticket sections or coupons for either a one way or a round trip passage, said strip being folded preferably by a roll fold 60 on the lines dividing said sections or coupons and being printed in the usual manner to denote the starting point, the destination that passage has been paid for, and the title of the transportation company issuing the same. 65

It also consists in providing a designated primary punch point on each ticket section or coupon through which the ticket is to be punched while folded so that all succeeding section or coupons will be simultaneously canceled against sale and so that the ticket section or coupon taken up will be void against subsequent use. 70

It further consists in means to readily determine when the ticket sections or coupons are returned to the auditor's office whether or not they have been manipulated with a view of further using the same after being once used for passage by the pur- 75 chaser. 80

It further consists in the novel features of construction, arrangement of parts and of printed matter, to be hereinafter described and more particularly pointed in the 85 subjoined claims.

In the drawings,—Figure 1 is a view of a ticket unfolded, the same provided with my invention and consisting of four ticket sections or coupons. Fig. 2 is a perspective 90 view of the ticket shown in Fig. 1, with the four ticket sections or coupons folded. Fig. 3 is a perspective view of the ticket with the first ticket section or coupon removed. Fig. 4 is a perspective view of 95 the ticket as it appears after removing the second section or coupon. Fig. 5 is a perspective view of the ticket as it appears after removing the third section or coupon. Fig. 6 is a transverse section through the 100 folded ticket. Fig. 7 is a view of a ticket unfolded showing some of the punch circles, herein termed "secondary punch points," out of line with related punch circles on other ticket sections or coupons, 105 the last-mentioned punch circles being herein termed "designated primary punch points." Fig. 8 is a view of a return ticket comprising two ticket sections or coupons. Fig. 9 is an enlarged view of a ticket un- 110 folded, bearing instructions for the conductor and information for the passengers, the

ticket being enlarged to permit of disclosing said instructions and information.

Referring now to the drawings in detail, like numerals of reference refer to like parts 5 in the several figures.

The reference numeral 10 designates the entire ticket, which in the first six and last figures of the drawing comprises four ticket sections or coupons 11, 12, 13 and 14, the 10 ticket sections or coupons being similarly numbered, as at 15, or provided with other identifying data so that when disconnected and turned into the auditor's office the sections or coupons of each complete ticket 15 can be assembled, and any irregularity in canceling the same readily noted. The ticket illustrated in these figures is a return trip ticket in which the first section or coupon 11 is for passage from any point in 20 Buffalo to the city line thereof. The second ticket section or coupon 12 is for passage from the city line to Niagara Falls, which is the destination in one direction. The third ticket section or coupon 13 is for 25 the return passage from Niagara Falls to the Buffalo city line, and the fourth and last ticket section or coupon 14 is for passage from the Buffalo city line to any point within the city limits of Buffalo, which is 30 the final destination for which the ticket is issued.

Each of the ticket sections or coupons may bear the title of the transportation company issuing the same, and the last section or coupon of the series bears the ticket agent's or some other official's signature or a facsimile thereof, as shown at 16. Each of the ticket sections or coupons has a notice to passengers and instructions to the conductor or other employee designated to collect the tickets for transportation. For example, the first ticket section or coupon 11 may bear the following information and instructions, viz.,—"Notice to passengers." 45 "This ticket is void for passage when detached from ticket section or coupon having signature of ticket agent and in such case will only be valid for redemption at any of the company's offices for its proportionate value when presented for such redemption by purchaser." "The conductor must at time of collecting this ticket punch out the X in view of passenger without unfolding and before detaching." Similar notice 50 is to be printed on the second and third ticket sections or coupons 12, 13, respectively, with the addition to the second ticket section or coupon 12 of the following or other printed matter, viz: "This ticket is 55 provided with a circle through which conductor's canceling punch penetrates from back, which denotes that such canceling was properly performed", and the following or other additional notice to the third ticket 60 section or coupon 13, viz.,—"This ticket is 65 provided with two circles through which conductor's canceling punch penetrates from back which denotes that such canceling was properly done." The fourth or last coupon of the series may bear the following notice, 70

viz.,—"This ticket is provided with three circles through which conductor's punch penetrates from back which denotes that such canceling has been properly done." While the above notices are now believed to 75 be sufficient for the purpose for which my invention was designed, it is of course apparent that any other notices, instructions or agreements may be added to or substituted for the above notices, if thought advisable to 80 do so, as such additions and substitutions are merely matters of choice of language and privileges falling fairly within the rights of any user of this invention.

Each of the ticket sections or coupons 85 has a designated primary punch point 17 preferably along its lower marginal portion, which primary punch point may be designated in any desired manner, the particular manner shown comprising a circle surrounding an X, and each of these designated primary punch points appears on the outside of the ticket as it is presented for cancellation by the purchaser. In line with each of the designated primary punch 90 points are related secondary punch points on all succeeding ticket sections or coupons, as clearly shown in Fig. 1, which secondary punch points are to be punched only when punching the designated primary punch 95 points related thereto.

When the ticket shown in Fig. 1 is presented by the purchaser to the conductor, the latter punches the same through the designated primary punch mark 17 on the first 105 ticket section or coupon 11 which causes the secondary punch points 18 on all succeeding sections or coupons related to said primary punch point 17 to be unpunched at the same time. After punching the ticket the conductor detaches the first ticket section or coupon and returns the remainder of the ticket to the passenger. The passenger will find each of the remaining ticket sections or coupons punched to show that the conductor 110 has properly canceled the first ticket section or coupon while the ticket was folded. The punching of said related secondary punch points of the remaining ticket sections or coupons also gives notice to the public that 115 the ticket has been presented for at least a portion of the trip for which it was purchased, and that the conductor offering the ticket for sale is trying to fraudulently dispose of it for the purpose of retaining for 120 himself the proceeds thereof or at least a portion of the proceeds. It is of course to be understood that when the conductor detaches the first ticket section or coupon from 125 the ticket he must record a unit on a fare 130

recorder, such as commonly used, and consequently must make returns to the auditor's office for the ticket taken up. The removal of the first ticket section or coupon entitles 5 the passenger to passage from any point within the city of Buffalo to the city line. Upon reaching the city line the conductor must take up the second ticket section or coupon 12 for passage from the Buffalo city 10 line to Niagara Falls. Before detaching, however, it is necessary that he cancel the ticket when folded substantially in the manner shown in Fig. 3. The designated primary punch point 17 of said second ticket 15 section or coupon is exposed to view, as clearly shown in Fig. 3, and when he punches through this punch point the succeeding ticket sections or coupons are punched simultaneously at the secondary punch points 20 19 related to said designated primary punch point 17. When the second ticket section or coupon is detached the conductor records a unit on the recorder within the car, and as it is necessary to cancel the second ticket section or coupon while the entire ticket is 25 folded in order that related secondary punch points 19 of the remaining ticket section or coupon are punched out, it will be impossible for him to detach said second ticket section 30 or coupon with a view of again disposing of the same. However, as now practised, the second ticket section or coupon is simply detached and the conductor given the privilege of canceling the same after being detached, 35 which a dishonest conductor oftentimes purposely fails to do, so that when he records a unit on the recorder he may retain the detached ticket section or coupon, and in place of the same substitute a cash fare of five cents. As the value of the detached coupon 40 is considerably more than five cents, he can later sell the same to another passenger and even then repeat the same fraudulent operations a number of times, retaining all received 45 above five cents, which amount, at least, must be turned into the auditor's office to agree with the number of units recorded on the recorder. By the use of a designated primary punch point on each of the ticket 50 sections or coupons and related secondary points on each succeeding section or coupon all the ticket sections or coupons are canceled against sale immediately the first ticket section or coupon is detached, and the sale is 55 further guarded against by canceling all of the remaining ticket sections or coupons each time a ticket section or coupon is detached from the ticket. When the passenger reaches his one way destination he finds 60 he is in possession of the second half of the ticket, which in this instance consists of two ticket sections and coupons good for return passage, and as the designated punch point with the X marks remain still unpunched, this portion of the ticket is valid 65

for the return trip, although if an attempt were made to dispose of the ticket by a conductor or any other party the fact that the secondary punch points 18, 19 have all been punched shows that the ticket has been used 70 by some other party and particularly shows, if offered by the conductor, that he is fraudulently disposing of the same.

This invention will also guard against the conductor using a return trip ticket for 75 two one way fares of two different passengers. For example,—a party entering the car at Buffalo and wishing a one way ticket for passage from Buffalo to Niagara Falls, would be compelled to pay at least three-fourths of the amount for which he could obtain return passage. Without the use of my invention the conductor could separate a return trip ticket on the divisional line between the second and third ticket sections 80 or coupons, obtaining for the first or "going" portion of the ticket the sum of forty cents. The other or "return" portion the conductor could retain until some passenger desired one way transportation from Niagara Falls to Buffalo for which the passenger would pay forty cents, making a total of eighty cents received by the conductor, and as the price of a round trip ticket would be only fifty cents, he could turn into the auditor's office fifty cents for the ticket sold, retaining thirty cents for himself. As it is necessary that tickets embodying my invention have all of the ticket sections or coupons punched prior to detaching the first 85 ticket section or coupon it would be impossible for the conductor to sell the return portion of the ticket to another passenger desiring one way transportation, as the punched out secondary punch points 18, 19 on the return portion of the ticket would immediately show that the conductor was fraudulently offering the ticket and was dishonest. 90

If a passenger having obtained passage 100 from Buffalo to Niagara Falls and return, desired return passage with the return portion of his ticket, which comprises the third and fourth ticket sections or coupons, the conductor takes up the ticket as presented to 105 him, in the form shown in Fig. 4, and punches the designated primary punch point 17 on the third ticket section or coupon, which simultaneously causes the related secondary punch point 20 on the last ticket section or coupon to be punched, and when reaching the city line of Buffalo there remains the designated primary punch point 17 on the last coupon to be punched. If, for example, the auditor or his assistants grouping the ticket sections or coupons according to number or other identifying data, wishes to determine whether each of the designated punch points were punched with their related secondary punch points at one opera- 110 115 120 125 130

tion, it is merely necessary to place the ticket sections or coupons in successive order with the edges even, and if the punch openings do not register there is cause for belief that the 5 conductor has manipulated the cancellation of the ticket sections or coupons in a manner contrary to instructions and evidently for the sole purpose of retaining a portion of the proceeds for himself, turning into the 10 company only such amount as the units recorded on the fare recorder may compel him. When a conductor is suspected by the auditor, a ticket such as shown in Fig. 7 may be given him among the regular tickets shown 15 in Fig. 1, the ticket shown in Fig. 7 being what may be termed a "test ticket" printed solely for the purpose of ascertaining whether the secondary punch points are punched separately from the designated 20 primary punch points with which they are related. In this test ticket one of each of the secondary punch points may be printed out of line with the related designated primary punch point, as shown at 21, 22, respectively, 25 and the secondary punch point 20 may also be printed out of line with its related designated primary punch point so that without notice to the conductor and with the strict instructions that the designated primary 30 punch points must be punched out centrally, it would be an easy matter to detect fraudulent operation on the part of a conductor; who, if he failed to cancel the ticket sections or coupons when folded and prior to 35 detaching them, would separately punch through the related secondary punch points and without knowledge that at least one of the secondary punch points is offset with respect to its related designated primary punch 40 point and its related secondary punch points, if any, his efforts would be to centrally punch through the exposed secondary punch point for the sole purpose of avoiding detection. In doing so he would positively show that 45 he has been improperly canceling the tickets for the sole purpose of retaining for himself a portion of the money paid by the passenger for transportation.

With return tickets from one town to another comprising two detachable sections or coupons, such as shown in Fig. 8, it is the practice at present for the conductor to detach the going portion of the ticket and hand the passenger the return portion. The conductor is of course supposed to cancel the going portion of the ticket, but if he does not do so and records a unit on the recorder he may, if dishonest, retain the going portion of the ticket and with his returns to the 50 auditor substitute five cents, clearing for himself all above the five cents which the going portion of the ticket may be worth. On the return he may likewise retain the going portion of another return trip ticket 55 issued from the opposite end of the line and

manipulate this ticket in a like manner so that upon his return to the starting point he will have a complete ticket and when another passenger wishes a return trip ticket he will be in a position to retain for himself 70 the full amount of the ticket, less the two five cent fares which he has substituted for the portions of the ticket retained on the round trip previously made. But with applicant's invention he is compelled to punch 75 the ticket while folded and in doing so punches through the designated primary punch point 23 on the going portion of the ticket and at the same time through the related secondary punch point 24 on the return trip portion of the ticket. This does not invalidate the return trip portion of the ticket for transportation, but prevents the conductor when he takes up the return trip portion of the ticket, from retaining it for 80 himself and disposing of it on a later trip, as the passenger will know when he sees the secondary punch point punched that the conductor has fraudulently sold him a ticket and has undoubtedly retained the same 85 solely for the purpose of cheating the company out of a portion of the fare paid by a passenger. At the same time, by compelling the conductor to punch the designated primary punch point of the going portion and the related secondary punch point of the return portion, it will be impossible for the conductor to retain the going portion; and if he severs the two portions one from the other and punches them separately, this can 90 be easily detected by matching the tickets in the auditor's office when returned.

It will be clear from the foregoing that any number of ticket sections or coupons may constitute the complete ticket, and that regardless of the number of ticket sections or coupons used, there are provided on each of the sections or coupons a secondary punch point or points for each designated primary punch point except the designated primary 95 punch point on the last section or coupon.

It will be apparent from the foregoing description that the secondary punch points are desirable features of my invention, but with a designated punch point on each of the 105 ticket sections or coupons the same results may be obtained in a measure if the secondary punch points are omitted. By the use of the secondary punch points, however, detection of fraudulent manipulation of the 110 ticket can be more easily discerned and with the test ticket having at least one of the secondary punch points related to each designated primary punch point out of line with such designated primary punch point, the 115 detection can be made positive without careful scrutiny of the ticket.

It will be plain from the foregoing that the punching out of the secondary punch points does not invalidate the ticket against 120

use for transportation, but only against sale, and where it may be desirable to omit the secondary punch points, the punching of the ticket otherwise than through the designated punch points does not invalidate the ticket against use but only against sale.

Having thus described my invention, what I claim is,—

1. A transportation ticket comprising a plurality of ticket sections bearing like identifying data, the ticket being folded on a roll fold on lines between said sections and each section having a single designated cancellation punch point, the ticket bearing data requiring it to be punched through all sections simultaneously and the place of punching being determined by the designated punch point on the section only to be detached.
2. A transportation ticket comprising a plurality of sections folded on a roll fold on lines between the sections and bearing like identifying data, each section being provided with a single designated punch point, all of the sections except the first having a secondary punch point related to the designated punch point of each section except the last.
3. A transportation ticket having a plurality of sections folded on a roll fold on lines between the sections, the sections bearing like identifying data being adapted to be taken up successively, each section having a single designated cancellation punch point along its lower marginal portion adapted to be punched simultaneously with the remaining sections of the ticket while folded.
4. A transportation ticket having a plurality of sections folded on a roll fold on lines between said sections and bearing like identifying data, each section having a single designated primary punch point and each section except the first having a secondary punch point related to the primary punch point on each of the preceding sections of the ticket when folded and being adapted to be punched simultaneously with its related primary punch points while the complete ticket or unused portion of the ticket is folded, the primary punch point on the last section of the ticket being adapted to be punched separately.
5. A transportation ticket comprising a plurality of sections bearing like identifying data, said ticket being folded on a roll fold on lines between said sections and said sections bearing data requiring their being taken up successively and requiring the first section of the complete ticket or the first section of the remaining unused portion of the ticket to be punched for cancellation simultaneously with the remaining section or sections of the ticket when folded.
6. A transportation ticket comprising a

plurality of detachable sections folded on a roll fold on lines between said sections and bearing like identifying data, the first section having a single designated primary punch point and each of the remaining sections having a single designated primary punch point and a secondary punch point, said ticket being adapted to be punched simultaneously through the designated primary punch point of each section and its related secondary punch points when folded, the secondary punch points related to each designated primary punch points being arranged in alinement lengthwise of the ticket.

7. A transportation ticket having a plurality of sections and being folded on a roll fold on lines between said sections, each section having a single designated cancellation punch point and all but the first section of the ticket having a secondary cancellation punch point, the designated cancellation punch point of each section, except the last, having related secondary punch points on each of the succeeding sections, at least one of the secondary punch points related to each of the designated punch points except the last being out of alinement with its related designated cancellation punch point, said sections being successively detachable.

8. A transportation ticket comprising a plurality of sections folded on a roll fold on lines between said sections, said sections being detachable successively and each of the sections, except the last, bearing data requiring it to be punched for cancellation simultaneously with all the remaining sections.

9. A transportation ticket comprising a number of detachable sections folded on a roll fold on lines between said sections and bearing the signature of an official of the issuing party and the successive sections bearing data requiring each section to be punched for cancellation simultaneously with all of the remaining section of the ticket while the ticket or the unused portion of the ticket is folded.

10. A transportation ticket comprising a plurality of ticket sections having like identifying data, the ticket being folded on a roll fold on lines between said sections and bearing instructions requiring each section to be taken up to be punched with the remaining sections while folded therewith, said ticket bearing also data whereby the passenger may ascertain when any ticket section is taken up for passage whether or not the detached section has been properly canceled.

11. A transportation ticket comprising a plurality of ticket sections, said ticket being folded by means of a roll fold along lines between said sections, each of said sections bearing data instructing the conductor to punch all sections simultaneously when tak-

ing up one of said sections, and data to enable the passenger to ascertain whether the conductor has properly canceled the detached section.

- 6 12. A transportation ticket having two sections bearing identifying data, said ticket being folded on a line between said sections, each section having a single designated primary punch point and the second section 10 having a secondary punch point related to the primary punch point on the first section of the ticket and adapted to be punched

simultaneously with said primary punch point while the ticket is folded, the primary punch point on the second section of the 15 ticket being adapted to be punched separately.

In testimony whereof, I have affixed my signature in the presence of two subscribing witnesses.

Corrections in Letters Patent No. 1,107,743.

It is hereby certified that in Letters Patent No. 1,107,743, granted August 18, 1914, upon the application of Frank Batt, of North Tonawanda, New York, for an improvement in "Transportation-Tickets," errors appear in the printed specification requiring correction as follows: Page 1, line 15, for the word "or" read *on*; page 2, line 109, for the word "unpunched" read *punched*; and that the said Letters Patent should be read with these corrections therein that the same may conform to the record of the case in the Patent Office.

Signed and sealed this 6th day of October, A. D., 1914.

[SEAL.]

R. F. WHITEHEAD,

Acting Commissioner of Patents.
